UNITED STATES PATENT OFFICE.

THOMAS H. MARS, OF CHICAGO, ILLINOIS.

DROP-TROLLEY.

No. 892,279.

Specification of Letters Patent.

Patented June 30, 1908.

Application filed October 5, 1906. Serial No. 337,615.

To all whom it may concern:

Be it known that I, THOMAS H. MARS, a citizen of the United States, residing at Chicago, in the county of Cook and State of Illinois, have invented certain new and useful improvements in Drop-Trolleys, of which the following is a specification.

This invention relates to improvements in drop trolleys or trolley mechanisms of that character which automatically release and fall when the trolley wheel jumps the trolley wire.

The present invention embodies improvements upon a similar construction heretofore invented by me and made the subject of another application filed April 5, 1906, Serial No. 309,964.

Among the salient objects of the present invention are to substitute for the friction clutch of the former application a positive dogging device which operates to automatically lock the pole against rebounding after it has fallen; to so construct this dogging device that it performs the additional function of a stop which arrests the upward movement of the pole at a predetermined angle after it has jumped the trolley wire; to so construct the toggle lever mechanism that it operates automatically to carry into and out of operative position the dogging device at proper times; to improve the details of construction of the leverage mechanism whereby sufficient upward tension is maintained upon the trolley pole to prevent it from readily jumping the wire in passing under viaducts and the like notwithstanding it is depressed to an abnormally low angle and notwithstanding the leverage mechanism is so arranged that throughout the principal descent of the pole its effective upward tension decreases; to somewhat simplify and strengthen the construction of the parts and at the same time to secure increased reliability and ease of operation; and in general to provide an improved construction of the character referred to.

The invention consists in the matters hereinafter described, and more particularly pointed out in the appended claims.

The invention will be readily understood from the following description, reference being had to the accompanying drawings, in which—

Figure 1 is a view showing in side elevation the base end portion of a trolley pole mechanism embodying my invention; Fig. 2

is a plan view of the same; Fig. 3 is a view similar to Fig. 1 with the parts in that position which they occupy when the pole has jumped the wire, risen to its extreme angle, 60 released, and is about to descend.

Referring to the drawings, 1 designates as a whole a suitable base casting provided with a central upright pivot-stud 2 upon which is rotatably mounted a turret casting, designated as a whole 3. The turret casting is provided with transversely opposite alined main pivot studs 4 upon which are mounted the arms 6, 6, of a main yoke casting 5 which is socketed at its free end and receives the base end of the trolley pole proper 7. A main expansion spring 8 is mounted upon the trolley pole, having one of its ends resting against the end of the socket of the yoke casting 5 and engaging at its opposite end a 75 collar 9 mounted to slide upon the pole. The collar 9 is provided with oppositely disposed studs or ears 10 with which are adjustably connected the upper or outer ends of tension links 11. These links extend through the 80 ears and may be adjusted as to operative length by means of collars 12 and lock-nuts 13 mounted thereon.

A second pair of oppositely disposed and alined pivot studs 14 is provided upon the turret casting, and upon each of these studs is mounted a T-shaped toggle lever 15. The tension links 11 are respectively connected with the lower ends of the levers 15 by means of pivots 16. The upper ends of the levers 15 90 are pivotally connected with toggle links 17, the lower ends of which are in turn connected with pivot studs 18 upon the yoke casting located some distance from the main pivots 4 toward the swinging end of the pole. 95 These links 17 are slotted, as indicated at 19, throughout a considerable portion of their lengths so that the trolley pole may rise through a considerable angle without necessarily oscillating the levers 15, as will herein-after appear. Upon the upper end of the yoke casting at each side thereof are journaled rollers 20 and the tension links 11 are jointed, as indicated at 11', and, when the trolley pole approaches its lowermost position, the under edges of the tension links engage these rollers and flex the links, as shown clearly in Fig. 1.

Describing next the controlling and tripping mechanism, upon each of the main 110 pivot studs 4 is pivotally mounted a latch 21, the arm of which is normally held in a rear-

wardly and upwardly inclined position by means of a coiled spring 22 and is limited against upward movement beyond a definite angle under the tension of said spring by means of stop shoulders 23. The extremity of each latch arm is provided with a notch 24 which co-operates with a corresponding projection 25 formed upon the lower end of the corresponding toggle lever 15. In order to force the latch arms downwardly to release the toggle levers, a lug 26 is formed or mounted upon the yoke casting at each side thereof in suitable position to engage a corresponding tappet stud 27 adjustably threaded through an upstanding arm 28 formed integrally with the corresponding latch member 21. These parts are so related that the latches will be disengaged simultaneously and just before the trolley pole reaches its uppermost limit of movement.

Releasing the levers 15, which it will be understood sustain the tension of the main spring through the tension links 11, permits them to oscillate so that their lower ends approach the pivot studs 4 or main axis of the trolley pole. In order to arrest these levers when they are thus oscillated to a definite angle, crescent-shaped lugs 29 are provided upon the turret casting at each side thereof in the paths of the respective pivots 16 which connect the levers with the tension links; the levers being shown in this changed position in Fig. 3. The swinging of the toggle levers 15 in the manner described permits the trolley pole to fall as will be hereinafter described.

As the trolley pole approaches its upper limit of movement after jumping the trolley wire, it is important that it be arrested suddenly so as to rebound and drop quickly, and before the pole can encounter cross wires or otherwise damage the line structure. Accordingly I provide one or more dogging devices (a pair in the present instance) 30 taking the form of pawl arms pivotally mounted at their upper ends upon the same studs 20' which carry the rollers 20 and extending thence forwardly in position to overlie a stop plate or bar 31 rigidly mounted to extend across the front side of the turret casting, as seen clearly in Figs. 1 and 2. Each lever 15 has a forwardly projecting arm or extension 15' which carries a supporting stud 32 which in certain positions of the mechanism engages the under side of the corresponding dogging pawl and holds these latter free from the stop plate 31. In the position the parts assume when the trolley pole has been released and is about to fall (see Fig. 3) the main body of each toggle lever is approximately upright and its arm 15' tilted downwardly out of range of the corresponding dogging pawl, so that the latter rides across the upper edge of the stop plate. At the proper point each dogging pawl is provided

with a stop shoulder or notch 33 which in this position of the parts engages the stop plate and positively arrests the upward movement of the pole.

The toggle levers 15 remain in this upright position until the pole has fallen as far as it will under its own weight and until arrested by re-tensioning of the spring. Accordingly when the dogging pawls are retracted by the descent of the pole they still ride across the upper edge of the stop plate and at the proper points they are each provided with one or more notches 34 which re-engage the stop plate and lock the pole against rebounding.

The chief portion of the descent of the pole is accomplished without disturbing the toggle levers 15, this being permitted by reason of the lost motion connection between the slotted links 17 and said levers. After the pole has been arrested in its descent, the mechanism is restored to normal operative position by simply pulling down the pole still further which action through the said links 17 positively oscillates the toggle levers until they are re-engaged with their respective latches 21. This change of position of the toggle levers elevates the arms 15' thus lifting the dogging pawls free from the stop plate, so that when the conductor releases the tension on the cord, by means of which he has pulled down the trolley pole, the latter rises under the tension of the main spring and is adjusted to the trolley wire in the usual manner.

It is important to note that in mechanism constructed as described, the swinging of the normally fixed points of resistance, viz: the lower ends of the toggle levers from their normal position into engagement with the stops 29, relaxes the tension on the main spring but very slightly,—merely enough to insure the shifting of the levers from their normal position into engagement with the stops 29 when released. The pole is, however, permitted to drop because these points of resistance are brought so close to the fulcrum of the pole that the main spring no longer has sufficient power, acting as it then does under such small leverage, to hold the pole upright. Moreover, it is to be noted that during the descent of the pole the main spring is compressed but slightly until the lost motion in the links 17 is taken up, whereupon the further descent of the pole is resisted by an abrupt or rapid tensioning action upon the main spring. After the mechanism has been re-latched, however, it will be noted that during the rising movement of the pole there is a constant increase of leverage as the angle between the tension links and the axis of the pole increases so that notwithstanding the fact that the spring is slightly expanding the working pressure of the trolley wheel against the wire increases

as the pole ascends higher and higher. This is a feature which it is believed has not been present in trolley pole mechanisms of the prior art, and it is of distinct advantage inasmuch as it greatly minimizes the liability of the trolley jumping the wire under normal conditions.

As the trolley pole approaches a horizontal position, the angle between the tension links and the axis of the pole decreases to such an extent that the main spring would exert its tension to such disadvantage that the trolley pole would not have sufficient working pressure to hold it against the wire in case of passing underneath viaducts or other points where the wire is extremely low, were it not for the fact that the rollers 20 arrest the approach of the tension links towards a position in exact alinement with the pole, cause said links to buckle or flex at the joints 11' and thus prevent a decrease of the effective tension of the main spring below that point at which the said rollers come into action.

I claim as my invention:

1. In a trolley mechanism, the combination with a turret member and a pole pivoted thereon to oscillate vertically, of a toggle lever pivoted between its ends on said turret member, a main spring, a part actuated by said main spring, a link connecting the spring-actuated part with that end of the toggle lever nearer the pivotal axis of the pole, a link connecting the other end of said toggle lever with the pole at a point removed from the pivotal axis of the latter, a latch with which the toggle lever is adapted to engage, a tappet member moving with the trolley pole and adapted to engage the latch and release the toggle lever, and a dogging pawl arranged to automatically engage and lock the pole against rebounding after it drops.

2. In a trolley mechanism, the combination with a turret member and a pole pivoted thereon to oscillate vertically, of a toggle lever pivoted between its ends on said turret member, a main spring, a part actuated by said main spring, a link connecting the spring-actuated part with that end of the toggle lever nearer the pivotal axis of the pole, a link connecting the other end of said toggle lever with the pole at a point removed from the pivotal axis of the latter, a latch with which the toggle lever is adapted to engage, a tappet member moving with the trolley pole and adapted to engage the latch and release the toggle lever, a dogging pawl pivotally connected with the pole at a point removed from the main axis of the latter, a fixed stop upon the turret member arranged to coöperate with said dogging pawl, and a part moving with said toggle lever operating to hold the pawl free from the stop when the toggle lever occupies its normal or working position.

3. In a trolley mechanism, the combina-

tion with a turret member and a pole pivoted thereon to oscillate vertically, of a toggle lever pivoted between its ends on said turret member, a main spring mounted upon the trolley pole, a collar actuated by said main spring, a link connecting the spring-actuated collar with that end of the toggle lever nearer the pivotal axis of the pole, a lost motion link connecting the other end of said toggle lever with the pole at a point between the pivotal axis of the pole and the spring-actuated collar thereon, a latch with which the toggle lever is adapted to engage to hold the main spring tensioned, a tappet member moving with the trolley pole and adapted to actuate the latch to release the toggle lever, a dogging pawl pivotally connected with the trolley pole at one end, an extension upon the toggle lever arranged to support the free end portion of the dogging pawl, and a stop member carried by the turret member with which said dogging pawl is adapted to engage when the toggle lever is in unlatched position.

4. In a trolley mechanism, the combination with a turret member and a pole pivoted thereon to oscillate vertically, of a toggle lever pivoted between its ends on said turret member, a main spring, a part actuated by said main spring, a link connecting the spring-actuated part with that end of the toggle lever nearer the pivotal axis of the pole, a link connecting the other end of said toggle lever with the pole at a point removed from the pivotal axis of the latter, a latch with which the toggle lever is adapted to engage, a tappet member moving with the trolley pole and adapted to engage the latch and release the toggle lever, an arm-like extension projecting forwardly from said toggle lever, a dogging pawl pivotally connected with the trolley pole at a point remote from the pivotal axis of the latter and at its free end extending above and supported by said extension of the toggle lever, a stop upon the turret member, a stop projection upon the pawl member adapted to register with and engage the turret member stop when the trolley pole reaches its upper limit of movement, and a second stop projection upon the pawl member adapted to engage the turret member stop when the trolley pole has fallen to the point at which it tends to rebound.

5. In a trolley mechanism, the combination with a turret member and a pole pivoted thereon to oscillate vertically, of a toggle lever pivoted between its ends on said turret member, a main spring, a part actuated by said main spring, a tension link connecting the spring-actuated part with that end of the toggle lever nearer the pivotal axis of the pole, a lost motion link connecting the upper end of said toggle lever with the pole at a point between the pivotal axis of the latter and the connection therewith of the tension

link, a spring-actuated latch member pivotally mounted concentrically with the pivotal axis of the trolley pole, a tappet member moving with the trolley pole and adapted to engage the latch and release the toggle lever, a fixed stop upon the turret member located in the path of movement of the lower end of the toggle lever under the action of the main spring when the toggle lever is released, a dogging pawl connected with the trolley pole, and a part moving with said toggle lever arranged to normally support the dogging pawl in inoperative position and operating to bring the pole into operation when the toggle lever is unlatched and shifted to its releasing position.

6. In a drop trolley mechanism, the com-

bination with a turret member and a pole pivoted thereon to oscillate vertically, of a main spring mounted upon the trolley pole 20 at a point remote from said turret member, a lever mechanism, and a releasing mechanism, of a dogging or stop pawl pivotally connected to the trolley pole at a point remote 25 from the turret member, and means associated with the lever mechanism for throwing the stop pawl into operation to arrest the upward movement of the pole both at its upper limit of movement and at its rebounding point.
